UNITED STATES PATENT OFFICE.

SOLOMON A. WYRICK, OF PALESTINE, TEXAS, ASSIGNOR OF ONE-HALF TO P. BLANCHARD & SONS, OF PALESTINE, TEXAS, A FIRM.

PILOT FOR LOCOMOTIVES.

Application filed November 1, 1922. Serial No. 592,398.

To all whom it may concern:

Be it known that I, SOLOMON A. WYRICK, a citizen of the United States of America, residing at Palestine, in the county of Anderson and State of Texas, have invented certain new and useful Improvements in Pilots for Locomotives, of which the following is a specification.

This invention relates to improvements in 10 pilots for locomotives.

When it is necessary to repair or replace parts on the trucks of the locomotive, the pilot must be removed, and as such pilots are rigidly bolted to the buffer beam, this 15 operation requires considerable time and necessarily involves great expense and delay.

One of the principal objects of the present invention is to overcome this objection. I propose to provide a structure wherein the 20 pilot is formed in sections, which are hinged to the buffer beam and locked to the latter when in use, and capable of being unlocked and swung apart to readily permit a mechanic to have access to the parts under the 25 front of a locomotive requiring repair.

The invention also comprehends improvements in the details of construction and arrangement of parts, which will be hereinafter described and particularly pointed out 30 in the claims.

In the drawings:

Fig. 1 is a front elevation of a locomotive equipped with my improved pilot.

Fig. 2 is a plan view of the parts assembled in pilot forming relation in full lines and the sections open up in dotted lines.

Fig. 3 is a front elevation of a locomotive with my improved pilot attached and showing the pilot sections thrown open.

Fig. 4 is a detail section on the line 4—4 of Fig. 2.

1 indicates the usual buffer beam of a locomotive, and hinged thereto near opposite ends, is my improved pilot 2.

45 The pilot comprises two sections 3—3, hinged to the buffer beam near the outer ends thereof, as indicated at 4—4. As the two sections are exactly alike, I will describe but one. Each section comprises a substantially triangular shaped base 5, the rear edge 6 of which is in alignment with the buffer beam 1, and the inner edge 7 lies in the vertical plane of the center of said beam. Extending upwardly from the rear of the 50 base, some distance from the edge 7 and

adjacent the edge 6, is a vertical support 8, and from the top of this support and extending to the triangular edge 9 of the base, are inclined guards 10. The outer upper end of the support 8 is provided with a 60 hinge member 11, which cooperates with a hinge member 12, secured on the front of the buffer beam. On the inner top edge of the support 8, is secured a casting 12' provided with ears 13, between which is pivoted 65 a locking lever 14, which in operative position, engages behind the edge of the buffer beam as shown in the drawings. To the face of the inner guard 10 is fastened a horizontal member 15 of a platform 16, 70 located about midway of the height of the section, and to this member is secured short guards 17, which extend to the base 5, the construction affording a space for a coupler when the sections are arranged in operative 75 relation.

The meeting edges 7 of the respective sections are formed with cooperating means, as holes and lugs 20, to interfit when the sections are in operative relation, to prevent 80 relative vertical offset of the sections; similar means 21 being formed on the buffer beam 1 and cooperating parts of the sections for a similar purpose.

One platform member 16 is provided with 85 overhanging flanges 23, while the companion member 16' overlies the adjacent member and fits under the flanges 23 to form an interlocking connection to assist in holding the sections in operative relation. 90

In use, the two sections are swung toward each other on their hinges to form a complete pilot, the lugs and depressions 20 and 21 cooperatively engaging, and the platform members and flanges interlocking to assist 95 in forming the sections into a rigid unit. The locking levers 14 are then thrown down on their pivots to engage the rear edge of the buffer beam, which with the interlocking lugs and depressions and platform sections, 100 acts to effectively hold the sections to the beam in pilot formation.

When the sections are thus locked, it is obvious that I have provided an effective and substantial pilot, the arrangement of the 105 platform members serving to provide ready and convenient means for attaching a coupling to the beam.

In case the trucks or other parts under the front of the locomotive require repair or 110

replacement, the locking levers 14 are turned upwardly to disengage them from the beam, and then the section or sections can be swung outwardly on the hinges, as shown in dotted lines in Fig. 2 and in full lines in Fig. 3. Obviously with the sections swung to one side of the beam, a mechanic will experience little difficulty in gaining access to the parts of the locomotive in rear of the beam.

10 By the construction described, time, delay, and expense, are saved in repairing the parts under the front of a locomotive, and at the same time a strong and durable structure is provided when the sections are folded in 15 pilot formation.

What I claim is:

1. In a locomotive pilot, the combination with a buffer beam, of two pilot sections hinged to the buffer beam, means between the sections to assist in holding the sections together, and locking levers for securing the sections in pilot forming relation to the buffer beam.
2. In a locomotive pilot, the combination of a buffer beam, two pilot sections hinged to the buffer beam, locking levers pivoted on the inner upper portion of the two sections and adapted to engage the buffer beam to secure the sections to the beam in pilot forming relation.
3. In combination, a locomotive buffer beam, of a pilot, comprising two sections hinged to the buffer beam, each section hav-

ing an inwardly extended platform member, one of which extends over the other, means 35 on the platform sections to assist in holding the two sections in operative relation, means between the abutting edges of the sections to assist in holding the sections together, means between the buffer beam and the sections to assist in holding the sections together, and locking levers pivoted to the sections to lock the latter to the buffer beam.

4. In a locomotive pilot, the combination with a buffer beam, of two pilot-forming sections connected to said beam for swinging toward or from each other, each of said sections having triangular bases moving in a plane below the buffer beam and upwardly and rearwardly inclined guard bars extending from one edge of such triangular base.

5. In a locomotive pilot, the combination with a buffer beam, of two pilot-forming sections connected to said beam for swinging toward or from each other, each of said sections having triangular bases moving in a plane below the buffer beam and upwardly and rearwardly inclined guard bars extending from one edge of such triangular base, and means carried by the guard bars of each section to cooperate for holding the sections when the sections are in pilot-forming relation.

In testimony whereof I affix my signature.

SOLOMON A. WYRICK. [L. S.]
